UNITED STATES PATENT OFFICE.

RICHARD S. BICKNELL, OF NITRO, WEST VIRGINIA, ASSIGNOR TO ELIOT BICKNELL,
OF NEWTON HIGHLANDS, MASSACHUSETTS.

CALCULATING DEVICE.

Application filed April 4, 1922. Serial No. 549,390.

To all whom it may concern:

Be it known that I, RICHARD S. BICKNELL, a citizen of the United States, residing at Nitro, in the county of Putnam and State of West Virginia, have invented certain new and useful Improvements in Calculating Devices; and I do hereby declare the following to be a full, clear, and exact description of the invention, such as will enable other skilled in the art to which it appertains to make and use the same.

The invention to be hereinafter described relates to calculating devices, and more particularly to devices for calculating the price of wool per pound after the grease has been removed therefrom with consequent shrinkage.

The price of the grease containing wool and the percentage of shrinkage being known, the problem is to determine the price of a pound of clean wool. This price can be computed, but it is a time consuming operation with liability of error in the calculation.

Also, the prices per pound of the grease containing wool varies, and the shrinkage varies, so that in the absence of a calculating device, frequent computations would need to be made.

The aim and purpose of the present invention, therefore, is to provide a simple, cheap calculating device whereby the clean price of wool per pound for varying grease prices and shrinkage per pound, may be quickly, easily and accurately ascertained.

The character of the invention may be best understood by reference to the following description of an illustrated embodiment thereof shown in the accompanying drawing, wherein:

Fig. 1 is a view of one side of a calculating device embodying the invention;

Fig. 2 is a view of the opposite side of the device;

Fig. 3 is a view of one side of the slide removed from its holder; and

Fig. 4 is a view of the opposite side of the slide shown in Fig. 3.

Referring to the drawing, the illustrated embodiment of the invention shown therein, comprises a holder desirably in the form of an envelope or wrapper 1 which may be made of celluloid or other suitable material.

A slide 3 of carboard, celluloid or other suitable material, may have an area substantially equal to the size of the folder, and may slide therein with a fit of sufficient friction to hold the slide in different positions of longitudinal adjustment with respect to the holder. At opposite ends of the holder are thumb notches 5 exposing end portions of the slide to facilitate grasping and sliding of the slide relatively to the holder.

The holder has an elongated aperture 7 (Fig. 2) in the reverse side thereof, and on a margin of the holder extending along one side of said aperture is a scale 9 having graduations marked with numbers, arranged in arithmetical progression and representing known values, such, for example, as the known grease prices of wool per pound.

The obverse side of the holder has an aperture 11 therein. On a margin of the holder adjacent this aperture is a scale 13 having graduations marked with numbers forming a continuation of the scale 9. On a margin of the holder at the opposite side of the aperture 11 is a scale 15 having graduations marked with numbers forming a continuation of the scale 13.

On the reverse side of the slide 3 referred to, is a scale 17 (Fig. 4) marked with numbers arranged in arithmetical progression and representing percentage values, such, for example, as percentages of shrinkage of wool per pound. On the obverse side of the slide is a scale 19 (Fig. 3) similar to the scale 17.

The scale 17 is so located on the slide, that it may be visualized through the aperture 7 in the reverse side of the holder, and the percentage numbers may be read in connection with the grease price numbers on the scale 9. The scale 19 is so disposed on the slide, that it may be visualized through the aperture 11, and the percentage numbers thereof may be read in connection with either of the grease price scales 13 and 15.

The slide has a scale 21 on the reverse side thereof having graduations marked with numbers representing the values to be determined, such, for example, as the clean prices of wool per pound. These numbers may be visualized through an aperture 23 (Fig. 2) in the reverse side of the holder,

and said numbers may be read in connection with an index 25 on the holder adjacent the aperture 23.

Also, on the reverse side of the slide is a scale 27 having graduations marked with numbers representing clean prices of wool per pound, said numbers being visualized through an aperture 29 in the reverse side of the holder, and the numbers of the scale 27 may be read in connection with an index 31 on the reverse side of the holder adjacent the aperture 29.

On the obverse side of the slide is a scale 33 (Fig. 3) having graduations marked with numbers representing clean prices of wool per pound. These numbers may be visualized through an aperture 35 in the obverse side of the holder, and said numbers may be read in connection with an index 37 on the holder adjacent said aperture.

On the obverse side of the slide is another scale 39 having graduations marked with numbers representing clean prices of wool per pound. These numbers may be visualized through an aperture 41 in the obverse side of the holder, and said numbers may be read in connection with an index 43 on the holder adjacent said aperture.

On the obverse side of the slide is another scale 45 having graduations marked with numbers representing clean prices of wool per pound. These numbers may be visualized through an aperture 47 in the obverse side of the holder, and may be read in connection with an index 49 on the holder adjacent said aperture.

On the obverse side of the slide is still another scale 51 having graduations marked with numbers representing clean prices of wool per pound. These numbers may be visualized through an aperture 53 in the reverse side of the holder, and said numbers may be read in connection with an index 55 on the holder adjacent said aperture.

If the known grease price of the wool appears on the reverse side of the holder, the slide is adjusted to bring the number representing the known percentage of shrinkage opposite the grease price number, and then a number on one of the clean price scales 21 and 27 will be visible through one of the apertures 23 and 29 in registration with one of the indexes 25 and 31, and this will indicate the clean price of the wool per pound.

If the known grease price appears in the scale 13 on the obverse side of the holder, and the slide is adjusted to bring the known shrinkage percentage in registration with said grease price, the clean price will be visible through one of the apertures 35 and 41 in registration with one of the indexes 37 and 43, and this will indicate the clean price of the wool per pound.

If the known grease price of the wool is

in the scale 15 on the obverse side of the holder, the clean price will be visible through one of the apertures 47 and 53 in registration with one of the indexes 49 and 55, and this will indicate the clean price 70 of the wool per pound.

If desired, the numbers of the scales 13, 33 and 39 which are read together and appear at the left of the elongated aperture 11 on the obverse side of the holder, may be 25 printed in black; whereas, the scales 15, 45 and 51 which are read together and appear at the right hand side of said aperture, may be printed in red, thereby further to distinguish between the left and right hand scales. 80

Each of the grease price scales is marked "Grease price", the apertures through the shrinkage scales are visible, are marked "Shrinkage", and the apertures through which the clean price scales are visible, are 85 marked "Clean price."

The clean prices are determined by computation. For example, if the grease price per pound of wool is 40¢, and its shrinkage after being cleaned is 20%, then $\frac{1}{5}$ of 90 a pound of clean wool costs 40¢, and one pound of clean wool would cost 50¢, the latter amount being determined by dividing 40¢ by 80 and multiplying the result by 100.

This computation may be determined by 95 the following equation or formula:—

$$C = \frac{100G}{100 - P}$$

in which C represents the cost of a pound of clean wool, G represents the cost of a pound of grease wool, and P represents the percentage of shrinkage of the wool resulting from removal of the grease therefrom.

Applying the above example in this equation,

$$C = \frac{40}{100 - 20} \times 100 = 50\text{¢}.$$

In using the calculating device, assuming the cost of the grease wool to be 40¢, and its shrinkage when cleaned to be 20%, to determine the cost of a pound of clean wool, the slide is adjusted longitudinally in its holder until 20% on the scale 19 is in registration with 40¢ on the scale 15. Then 50¢ in scale 45 will be visible through the aperture 47 and in registration with the index 49, thereby indicating that the price of a 120 pound of clean wool is 50¢.

Referring to Fig. 1, the slide has been adjusted for the computation in which the grease price of a pound of wool is 60¢, and the shrinkage is 64%. Therefore, 64% in 125 scale 19 is in registration with 60¢ in scale 15, and the clean price visible through the aperture 47 in registration with the index 49, is \$1.66, thereby indicating that the price of a clean pound of wool is \$1.66. In a 130

similar way the clean prices based on various known grease prices and shrinkages may be determined.

The several grease price scales are virtually one continuous scale, but by dividing this continuous scale into several scales, the length of the device is desirably shortened.

This calculating device is simple and compact in construction, and may be placed in the pocket of the user, where it will always be ready for use. By a very simple operation, the user can quickly and accurately determine the clean price per pound of wool for various known grease prices per pound of wool and various shrinkages.

Another use which may be made of this calculating device is to place the index against the assumed clean price of the wool. For example, assume that by examination of a given sample of wool it is the judgment of the observer that its clean price would be 95 cents per pound. Then, by looking at the shrinkage scale the observer would know what the grease price would be within various limits of shrinkage per cent. Thus, considering that the shrinkage would be between 60% and 65%, it would be apparent that the grease price would be between 33 and 38 cents per pound. This use of the device is alike of value to the wool buyer and to the wool seller, the wool buyer in fixing the price he can offer for the wool, and the seller in estimating the market price of the wool he has for sale.

The word "shrinkage" as used herein is the per cent of diminution of weight of the wool due to the cleaning process. This is the terminology used in the American market. In the British, Australian, New Zealand and other foreign markets the term "shrinkage" is not used, but the word "yield" is used, and the scale that would be used in the device in such places would, instead of having the per cent of shrinkage printed thereon, have the per cent of yield printed thereon, which would be the difference between the percentage furnished and 100. Thus, instead of 10, 90; instead of 15, 85; etc.

It will be understood that the invention is not limited to the specific embodiment

shown, and that various deviations may be made therefrom without departing from the spirit and scope of the appended claims.

What is claimed is:

1. A calculating device having, in combination, two relatively sliding members having adjacent computing scales, one of the members being provided with two non-aligned result scales and the other member having two indexes whereby the result of the computation may be read against either one of the indexes. 55

2. A calculating device having, in combination, a holder having an elongated opening and two non-aligned apertures, the holder being provided with a scale adjacent the margin of the elongated opening and an index adjacent each of the apertures, and a slide having a computing scale adapted to 60 be set selectively with respect to the holder scale, and two scales upon one of which the result may be read adjacent one of the indexes on the holder. 65

3. A calculating device having, in combination, a holder provided with an elongated central opening, number scales adjacent the margins of the opening, one of the scales being a continuation of the other, a slide having a computing scale common to both 70 of the holder scales, and a pair of result indicating scales for each of the holder scales, the holder being provided with four indexes, one for each result indicating scale of the slide, whereby the result is indicated against 75 one of the indexes regardless of the position of the slide. 80

4. A calculating device having, in combination, a holder having an elongated opening with a logarithmic scale adjacent the margin thereof and two non-aligned sight apertures, a slide having three logarithmic scales, one of which is visible through the central opening of the holder and the other two being visible through the apertures in 90 the holder, the holder being provided with indexes on the margins of the sight apertures, the slide being adapted to be set relatively to the holder scale for a mathematical computation, the result of which may be 95 read against one of the indexes. 100
